(57) **CLAIM**

The ornamental design for a key case, as shown and described.

DESCRIPTION

FIG. 1 is a front, right, and top perspective view of a key case, showing my new design;

FIG. 2 is a rear, left, and bottom perspective view thereof;

FIG. 3 is a front elevation view thereof;

FIG. 4 is a rear view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings are included for the purpose of illustrating portions of the key case that form no part of the claimed design.

1 Claim, 8 Drawing Sheets
